UNITED STATES PATENT OFFICE.

CHESTER E. RAHR, OF BROOKLINE, MASSACHUSETTS, ASSIGNOR TO THE FLINTKOTE COMPANY, OF BOSTON, MASSACHUSETTS, A CORPORATION OF MASSACHUSETTS.

ROOF-SHINGLE.

1,340,348.

Specification of Letters Patent.

Patented May 18, 1920.

Application filed December 27, 1919. Serial No. 347,679.

To all whom it may concern:

Be it known that I, CHESTER E. RAHR, a citizen of the United States, residing at Brookline, in the county of Norfolk and 5 State of Massachusetts, have invented new and useful Improvements in Roof-Shingles, of which the following is a specification.

This invention has relation to asphalt shingles, and more particularly to what are known commercially as "wide space" shingles. Such shingles ordinarily are formed 10 of roofing felt impregnated with an asphaltic or bituminous composition and surfaced with crushed slate or other granular or flaky mineral material partially embedded in an 15 asphalt coating. Such shingles are more or less flexible, and may be laid with wide spaces between them to form a roof covering as illustrated and described in United 20 States Letters Patent to Calvin Russell, No. 1,145,440, dated July 6, 1915, in which case each shingle, in bridging two adjacent shingles in the same horizontal row, sags or bends downwardly more or less to fill the 25 gap or space between them.

The present invention has for its object so to form the shingles as to insure their being laid in proper relation by unskilled workmen, and also to insure the contact of 30 each shingle, bridging a gap or space, with the shingle therebeneath.

On the accompanying drawing,—

Figure 1 illustrates a shingle embodying the invention.

Fig. 2 represents a cross section on the line 2—2 of Fig. 1.

Fig. 3 illustrates a portion of a roof covering consisting of the said shingles.

Fig. 4 represents a section on the line 40 4—4 of Fig. 3.

Fig. 5 shows one way of making the shingles.

Roofing shingles are customarily made of absorbent paper felt, which is flexible, and 45 which is saturated with any usual waterproofing asphaltic or bituminous compound having a relatively low melting point, but may be otherwise made of a suitable fibrous material and a waterproof binder. A sheet 50 of the saturated felt or other equivalent foundation, is coated with asphalt or pitch having a melting point sufficiently high to prevent its being unduly softened by solar heat, and in the coating is partially em-

bedded a thick layer of flaky slate or other 55 crushed mineral material of the desired color. It is customary to cut such a sheet by suitable instrumentalities into oblong shingles of the desired length and breadth.

In accordance with the present invention, 60 however, such shingles are provided with marginal portions along their side edges which are not surfaced with the mineral material, such uncoated portions, however, terminating at a distance from the lower 65 edge of the shingle, so that the lower end of the shingle is surfaced from one side edge to the other, with a band of the mineral material, all for a purpose to be explained.

Referring to the drawing,—a shingle is 70 illustrated as consisting of a body of felt *a* impregnated with a suitable pitch or bitumen, and having a coating *b* of higher-melting-point pitch or bitumen. A portion of the face of the shingle is surfaced with 75 a thick layer of crushed slate or its equivalent as indicated at *c*. The shingle thus formed is flexible and may bend without injury. Such shingles to be laid between them may, for example, in full size be approximately nine inches wide by fourteen inches long, though of course, they may be made in various sizes. It will be observed that each shingle has side marginal strips or portions *d* which are not provided with 80 the surfacing material. These unsurfaced strips extend from the upper edge of the shingle to a transverse line which may, for example, be located about four inches (more or less) from the lower edge of the shingle, 85 and each unsurfaced strip may in such case be about one and one-half inches wide. Thus the surfaced portion of the shingle somewhat resembles an inverted *T*. The width of the strips determines the extent to 90 which each shingle is laterally overlapped by the contiguous shingles of the superimposed horizontal row, and the length of the strips determines the extent to which the shingles of each row project below the shingles of said superimposed horizontal row. 95 Thus the strips determine the width of the gaps or spaces between the shingles of each horizontal row, and also the extent to which one horizontal row of shingles is overlapped by the next succeeding horizontal row. The inner end and side edges of each strip are 100 marked by a shoulder *e* formed by the sur-

facing material, and against which the complementary corners of the laterally overlapping shingles may be abutted.

The shingles may be formed from a sheet as shown in Fig. 5. That is to say, when the sheet of felt 10 is being surfaced with the slate, certain portions or oblong areas as at 11, 12, may be left uncoated, and then the sheet may be slit longitudinally on the lines 13—13 and severed transversely on the lines 14—14, 15—15, so that each shingle thus formed will have the uncoated strips *d* as shown in Fig. 1. The oblong unsurfaced areas are shown as arranged in transverse rows, and extend individually longitudinally of the sheet, those intermediate the edges being bisected between their ends and midway between their side edges.

When the shingles are laid upon the roof, they are arranged in horizontal rows, and in each row are spaced apart a distance equal to the width of the mineral facing on the upper end of the shingle as indicated at 20 in Fig. 3. When the second row 21 is laid, each shingle laterally overlaps the strips *d* of the shingles of the first row, and is abutted against the shoulders *e* thereof which form a reentrant right angle complementary to the corner of the shingle. The third row 22 is similarly laid on the second row, with the result that, when the roof covering is finished, all of the unsurfaced areas are concealed, the adjacent shingles of each row are properly spaced, and each row of shingles overlaps the row on which it is superposed.

When the shingles have been laid with wide spaces between them as described, with each one bridging a wide gap between two shingles of the next lower row, it bends or sags downwardly so as to make contact with the shingle immediately beneath it (*i. e.* the corresponding shingle of the second lower row) and closes the gap. Since each shingle laterally overlaps only the unsurfaced strips *d*, the initial space, between it and the shingle immediately beneath the gap bridged thereby, is greatly reduced, being much less than if each shingle were entirely surfaced with crushed slate.

While I have described the shingle as

having no surfacing material exposed at the strips *d*, it is evident that substantially the same results may be secured by 55 initially surfacing these areas with crushed slate, and then completely embedding the slate in these areas so as to expose the black asphalt coating. In each case, the exposed grit or slate is absent in these areas, and the asphalt coating is exposed. In each case, inaccuracies in laying the roofing are quickly shown by exposure of the black coating, for, when the shingles are properly laid, the black areas or strips *d* are 60 entirely covered.

If it be desired to lay the shingles with a space of, say, one-half inch between those in the same row, the strips *d* will be much wider, so as to leave between them only a 70 narrow surfaced strip extending downwardly from the upper edge of the shingle and merging in the broad horizontal band of surfacing material, which crosses the entire lower end of the shingle. 75

What I claim is:

1. A flexible asphalt shingle, having a coating of asphalt and a surface layer of crushed mineral material partially embedded therein, and having, along its side edges, marginal portions in which the asphalt coating is exposed, said marginal portions terminating in a transverse line spaced from the bottom edge of the shingle. 80

2. A flexible asphalt shingle, having a 85 coating of asphalt and a surface layer of crushed mineral material partially embedded therein, and having oblong areas extending from the upper edge thereof along its side edges to a transverse line parallel 90 to and spaced from the lower edge of the shingle in which the asphalt coating is exposed to be overlapped by the corners of contiguous shingles.

3. A flexible asphalt shingle, having a 95 coating of asphalt and an exposed layer of crushed mineral material extending across and covering the entire lower end, and extending therefrom to the upper edge of the shingle except at marginal areas at 100 the sides of the shingle.

In testimony whereof I have affixed my signature.

CHESTER E. RAHP
